UNITED STATES PATENT OFFICE.

WIDLER S. SPONHAUER, OF FORT WAYNE, ASSIGNOR OF ONE-HALF TO
WILLIAM ROGERS, OF ALLEN COUNTY, INDIANA.

BUCKLE.

SPECIFICATION forming part of Letters Patent No. 258,326, dated May 23, 1882.

Application filed April 8, 1882. (No model.)

To all whom it may concern:

Be it known that I, WIDLER S. SPONHAUER, of Fort Wayne, Allen county, Indiana, have invented certain Improvements in Buckles, of 5 which the following is a specification.

My invention is a buckle constructed, as fully described hereinafter, so as to be readily applied to and adjustably unite heavy straps, such as are used for harness.

10 In the drawings, Figure 1 is a perspective view, showing a part of a trace with my improved buckle. Fig. 2 is a longitudinal section of Fig. 1. Fig. 3 is a side view, the buckle open. Fig. 4 is a perspective view of the parts detached.

15 The buckle consists of three parts—the loop A, having curved side arms *a a* and cross-bars *b e*, the latter receiving the loop of the strap B, the tongue-plate D, carrying a pin, *d*, and provided with curved side arms *f f*, connected by a cross-bar, *e*, and the union-plate E, having side pieces, *g g*, cross-bars *h h'*, the latter notched at *x*, arms *l l*, with notches *y y*, connected by a cross-rod, *m*. The side pieces, 20 *g g*, have notches *s s*, through which the side arms *a a* of the loop A extend when the parts are in the positions shown in Figs. 1 and 2, the upper strap, H, extending between the side bars through the loop A, and also between 25 the arms *f f* of the tongue-plate D, which extend through the slots *y y*, thus serving to connect all the parts loosely together, which otherwise can be easily separated.

When the end of the strap H is introduced 35 the parts are arranged as shown in Fig. 3, permitting the strap to slide in or out until properly adjusted, when the plate D is turned down flat upon the strap, with its pin *d* in one of the holes of the strap. The strap B is then pulled out, when the loop A will be turned down with 40 its cross-bar *b* bearing upon the tongue-plate D with a force proportioned to the draft.

By this construction I can readily unite the heaviest straps, yet permit instant adjustment or detaching when necessary.

45 It will be seen that the parts may be readily and cheaply cast and fitted together without nice finishing.

I claim—

The combination, in a buckle, of a loop, A, 50 having side arms and cross-bars, a lock-plate, D, provided with a pin, *d*, arms *f f*, and cross-bar *e*, and a union-plate E, having recessed side pieces, *g g*, cross-pieces *h h'*, notched arms *l l*, and a cross-bar, *m*, all substantially as set 55 forth.

In testimony whereof I have signed my name to this specification in the presence of two subscribing witnesses.

WIDLER S. SPONHAUER.

Witnesses:

WILLIAM ROGERS,
MARTIN O. SENSENY.
